UNITED STATES PATENT OFFICE.

TRAVIS OAKES, OF MOUNT VERNON, OHIO, ASSIGNOR TO PITTSBURGH PLATE GLASS COMPANY, A CORPORATION OF PENNSYLVANIA.

APPARATUS FOR SEVERING GLASS SHEETS.

Application filed November 25, 1925. Serial No. 71,452.

The invention relates to apparatus for successively severing or separating glass sheets from a continuously formed ribbon and constitutes an improvement upon, or more exactly, an addition to, the apparatus of the Slingluff Patent, Number 1,373,533, of April 5, 1923. In the use of the apparatus of said patent, after the glass was heated transversely by the nichrome ribbons, it was necessary for the operator to either score the edges of the sheet to start the crack along the line of heating, or to wet such edges slightly, so that a second operator was required in order to support the sheet and prevent its falling, while the first operator was scoring or wetting the edges of the sheet. The present invention is designed to do away with the requirement for the services of one of the operators. Briefly stated, this is accomplished by providing air chilling means for starting the crack along the line heated by the nichrome ribbons, such chilling means being operated by a valve worked by the foot of the operator, so that such operator has both hands free to support the sheet when the air is applied to the two edges of the sheet to start the crack. In applying the improvement, a pair of nozzles are preferably used, supplied through flexible hose, and carried by the counterweighted devices upon which the nichrome ribbons are mounted. The position of the nozzles is thus fixed with respect to the ribbons and with respect to the edges of the glass sheet, so that the chilling devices move with the ribbons and always apply the air at the same points. While a nozzle is preferably used at each edge of the sheet, it is possible to carry out the operation with one nozzle. The nozzles are preferably directed toward the center of the sheet, so that the air strikes the strip of glass which has been highly heated by the nichrome ribbons. One embodiment of the invention is illustrated in the accompanying drawings, wherein:

Figure 1 is a front view showing the apparatus applied at the upper end of a glass drawing machine. Fig. 2 is a side elevation. Fig. 3 is a plan view. Fig. 4 is an enlarged detail view. Fig. 5 is an enlarged side elevation of one of the solenoids and the operating means actuated thereby. And Fig. 6 is an enlarged detail section.

Referring to the drawings, 1 is a glass

sheet which is being drawn continuously in a vertical direction from a glass bath, not shown, the drawing means preferably consisting of a series of pairs of rolls 2, 3, etc., only the upper three of which are shown. These rolls are driven from the vertical shaft 4 through the intermediary of suitable gearing 5, 6 and 7, constituting no part of the present invention. As the glass rises continuously through the floor 8, it becomes necessary to cut it off in sections and place it upon suitable transfer means for carrying it to the cutting room. Such transfer means, in the present instance, is in the form of a truck 9 upon which the sheets 10 are stacked until the truck is filled, when it is removed and an empty one moved into its place. The means for cutting off the glass, preferably consists of a pair of bars 11, 11 carrying ribbons 12, 12 (Fig. 5) of high resistance material, such as "nichrome". The bars 11 are preferably in the form of channels carrying a backing of asbestos 13 for supporting the "nichrome" ribbons and thus insuring good contact with the surface of the glass from one side thereof to the other. The bars are supported at each end by a pair of brackets 14, 14 pivoted at their upper ends to the plates 15. The weight of the bars and their operating mechanism is counterweighted by means of the pair of cables 16, 16 passing around the pulleys 17 and 18 and provided at their other ends with the weights 19. Carried by the plates 15 are the solenoids 20, 20 for moving the bars 11, 11 towards each other to cause the ribbons 12, 12 to engage the glass sheet upon its opposite sides. Each solenoid carries a pair of depending brackets 21, 21 to which are pivoted the bell crank levers 22, 22 connected at their inner ends to the core 23 of the solenoid. The other ends of the levers are connected to the ends of the rods 24, 24 extending through the brackets 14, 14 and provided at their outer ends with the washers 25, 25. Intermediate the washers and the sides of the brackets 14, 14 are the springs 26, 26, so that when the rods are moved inward by the solenoid, the clamping bars will be given yielding engagement with the glass. The bars 11, 11 are normally held in their outer positions away from the glass by means of the springs 27, 27.

Also mounted upon the bars 11, 11 are

the pair of nozzles 28, 28 positioned as indicated in Figs. 3 and 4 with their inner ends closely adjacent the point where the contact between the "nichrome" ribbons and the glass sheet terminates, it being noted from Fig. 4 that the contact between the "nichrome" ribbons and the glass terminates short of the edge of such glass. The outer ends of the nozzles are provided with the 10 flexible supply pipes 29, 29 so that the nozzles can move up and down with the clamping bars 11, 11. The other ends of the pipes 29, 29 are connected to the branches 30, 30, supplied from the air pipe 15 31. As indicated in Fig. 2, the supply pipe 31 is located just beneath the floor of the cutting off room and is provided with a valve 32 having an operating stem 33 projecting through the floor. This valve is normally held closed by means of a spring 34. The amount of air which flows through the pipe 31 may be regulated by means of another valve 35, so that just the right amount of air may be supplied through the nozzles 25 28, 28 when the valve 32 is opened full.

In operating the device, current is sent through the windings of the solenoids 20 which causes the bars 11 to approach so that the "nichrome" bands 12, 12 engage the 30 opposite sides of the sheet. At the same time, current is supplied through the nichrome bands, the application of the current to the windings of the solenoids and the "nichrome" bands being preferably controlled by the actuation of a single switch. The bars then move upward with the sheet which is to be cut off, the weight lifted being reduced by reason of the counterweights 19, so that no undue strain is thrown upon 35 the glass. During this period of upward movement, the current passing through the "nichrome" bands, causes them to attain a high temperature and heat the strip of glass lying between the two bands. This contact is maintained a period of time, such as experience indicates as necessary, at which time the circuit through the solenoid windings and through the nichrome bands is broken, the springs 27, 27 at this time causing the bars 11, 11 to release the glass. At 40 this time, the operator grasps the glass above the bars and presses down the stem of the valve 34, so that a flow of air passes through the nozzles 28, 28 and against the end portions of the heated area of glass from which the "nichrome" ribbons have just been withdrawn. This sudden cooling of the highly heated glass causes it to crack 45 along the line of heating and clear out to the edges of the sheet, no scoring or wetting of the edge being necessary, as heretofore has been the case, so that the operator is free to use both hands to support the glass section which is cracked off. This section 50 is then placed upon the truck 9 and the supply means.

operation is repeated when another section of glass of the proper length has passed between the bars 11, 11. As heretofore indicated, the cracking off operation may be carried out with a single nozzle, but the 70 action is more certain when the two nozzles are used. Similarly, it is possible to carry out the cracking operation using only one "nichrome" ribbon, but here again the operation is more certain and effective if two 75 ribbons are employed, since the heating of the strip of glass is more rapid and positive with the two ribbons, and, in case the glass is not flat, the two ribbons insure contact across the entire sheet of glass which is not 80 the case where a single ribbon only is used. The situation of the air valve, as illustrated, is controlled by the feet of the operator, but this valve might be located at some other point and operated in some other way, if 85 desired. Some other cooling gas or vapor might also be used instead of air, such as steam, or a mixture of water vapor and air or of steam and air.

What I claim is:

1. An apparatus for separating sections from a continuously formed sheet of glass, comprising electric heating means extending transversely of the sheet, means for clamping the heating means against the sheet so that it moves along with the sheet during the heating operation, a nozzle at the edge of the sheet supported in fixed relation to the heating means, so as to move along therewith, fluid supply means therefor, and means for controlling the flow of fluid through said supply means.

2. An apparatus for separating sections from a continuously formed sheet of glass, comprising electric heating means extending transversely of the sheet, means for clamping the heating means against the sheet so that it moves along with the sheet during the heating operation, a nozzle at the edge of the sheet supported in fixed relation to the heating means, so as to move along therewith, fluid supply means therefor, and a foot valve located adjacent the sheet for controlling the flow of fluid through said supply means.

3. Apparatus for separating sections from a continuously formed glass sheet, comprising a pair of bars extending transversely on opposite sides of the sheet to be severed and free to move along with the sheet, electrical heated members extending longitudinally of the bars, means carried by the bars at their ends for clamping them together with the sheet between them, a nozzle at the edge of the sheet also carried by the bars and directed onto the surface of the sheet adjacent the point where the contact between the electrical heated members and the glass begins, fluid supply means for the nozzle, and means for controlling the flow of fluid through said supply means.

4. Apparatus for separating sections from a continuously formed glass sheet, comprising a pair of bars extending transversely on opposite sides of the sheet to be severed and free to move along with the sheet, electrical heated members extending longitudinally of the bars, means carried by the bars at their ends for clamping them together with the sheet between them, a nozzle at the edge of the sheet also carried by the bars and directed onto the surface of the sheet adjacent the point where the contact between the electrical heated members and the glass begins, fluid supply means for the nozzle, and a foot valve located adjacent the sheet for controlling the flow of fluid through said supply means.
5. An apparatus for separating sections from a continuously formed sheet of glass, comprising electric heating means extending transversely of the sheet, but of less length than the width of the sheet, means for clamping the heating means against the sheet so that it moves along with the sheet during the heating operation, a nozzle at the edge of the sheet supported in fixed relation to the heating means, so as to move along therewith, fluid supply means therefor, and means for controlling the flow of fluid through said supply means, the said nozzle being positioned so as to direct the fluid upon the sheet at the end of said heating means.
6. An apparatus for separating sections from a continuously formed sheet of glass, comprising electric heating means extending transversely of the sheet, means for clamping the heating means against the sheet so that it moves along with the sheet during the heating operation, a nozzle at each edge of the sheet supported in fixed relation to the heating means, so as to move along therewith, fluid supply means therefor, and means for controlling the flow of fluid through said supply means.
7. An apparatus for separating sections from a continuously formed sheet of glass, comprising electric heating means extending transversely of the sheet, means for clamping the heating means against the sheet so that it moves along with the sheet during the heating operation, a nozzle at each edge of the sheet mounted so as to move along with said heating means, fluid supply means for the nozzles, and a foot valve located adjacent the sheet for controlling the flow of fluid through said supply means.

In testimony whereof, I have hereunto subscribed my name this 19 day of Nov. 1925.

TRAVIS OAKES.
